CLAIM

The ornamental design for a bicycle frame, as shown and described.

DESCRIPTION

FIG. 1 is a side perspective view of my new design for a bicycle frame;
FIG. 2 is a rear perspective view thereof;
FIG. 3 is a front perspective view thereof;
FIG. 4 is a side elevational view thereof;
FIG. 5 is an opposite side elevational view thereof;
FIG. 6 is a rear elevational view thereof;
FIG. 7 is a front elevational view thereof;
FIG. 8 is a bottom plan view thereof;
FIG. 9 is a top plan view thereof;
FIG. 10 is a side perspective view of a second embodiment of my new design for a bicycle frame;
FIG. 11 is a rear perspective view of FIG. 10;
FIG. 12 is a front perspective view of FIG. 10;
FIG. 13 is a side elevational view of FIG. 10 thereof; and,
FIG. 14 is an opposite side elevational view of FIG. 10.
